UNITED STATES PATENT OFFICE

108,943

DESIGN FOR A TEXTILE FABRIC

August Hafner, Flushing, N. Y.

Application February 23, 1938, Serial No. 75,336

Term of patent 3½ years

To all whom it may concern:

Be it known that I, August Hafner, a citizen of the United States of America, residing in the city of Flushing, county of Queens, New York, have invented a new, original, and ornamental Design for a Textile Fabric, of which the following is a specification, reference being had to the accompanying drawing, forming part thereof, wherein,

The figure is a plan view of a piece of textile fabric showing my new design.

I claim:

The ornamental design for a textile fabric substantially as shown.

AUGUST HAFNER.
